N. S. Nedder, of Troy, N. Y.
Letters Patent No. 1040. - dated Aug. 10, 1858

The schedule referred to in these Letters Patent and making part of the same.

To all whom it may concern:

Be it known that I, N. S. Nedder, of the City of Troy, in the County of Rensselaer, and State of New York, have invented or produced a new and original Ornamental Design for Plates of an Oval Parlor Stove; & I do hereby declare that the following is a full and exact description of the same, reference being had to the annexed photographic drawings making a part of this specification, in which Fig: 1. represents the top plate and Fig: 2. the bottom plate of the Stove.

My ornamental design for plates of an oval parlor stove consists of the ornamented molding a, and convex open-work ornamented border b, formed and arranged together as shown in Fig: 1. and the concave ornamented border c, ornamented molding d, ornamented molding e, terminated by the scrolls f, and the ornamental scroll g, held open by the filigree-rod h, - all formed, and combined as shown in Fig: 2.

What I claim as my invention or production and desire to secure by Letters Patent is the Ornamental design herein described and represented in the annexed photographic drawings for the top and bottom plates of an oval parlor stove.

Witnesses.
